UNITED STATES PATENT OFFICE.

SIMO GJUKIĆ, OF COLUMBUS, OHIO.

LOCK.

1,375,287.

Specification of Letters Patent. Patented Apr. 19, 1921.

Application filed October 30, 1920. Serial No. 420,705.

To all whom it may concern:

Be it known that I, SIMO GJUKIĆ, citizen of Jugo-Slavia, residing at Columbus, in the county of Franklin and State of Ohio, 5 have invented certain new and useful Improvements in Locks, of which the following is a specification.

This invention relates to certain new and useful improvements in locks and has particular reference to a door lock wherein a sliding latch bolt is adapted to be shifted by a knob shank having a link connection with the inner end of the bolt.

A further object of the invention is to 15 provide a door lock wherein a sliding latch bolt is adapted to be engaged by a key operated tensioned latch device for retaining the bolt in its locked position, the opposite sides of the door being provided with differently shaped key receiving openings for 20 different keys for releasing the latch device from either side of the door.

With the above and other objects in view, the invention consists in the novel form, 25 combination and arrangement of parts hereinafter more fully described in connection with the accompanying drawings, and in which like reference characters indicate similar parts throughout the several views.

30 In the drawings,—

Figure 1 is a fragmentary sectional view of a portion of a door and casing with the cover of the lock casing removed and with portions of the lock mechanism shown in 35 section,

Fig. 2 is a horizontal sectional view taken on line II—II of Fig. 1,

Fig. 3 is an elevational view, similar to Fig. 1 showing the sliding latch bolt in its 40 retracted position with the key entering the outer side of the door retracting the latch device from engagement with the sliding latch bolt,

Fig. 4 is a horizontal sectional view taken 45 on line IV—IV of Fig. 3,

Fig. 5 is a fragmentary elevational view of the outer side of the door showing the shape of the key hole,

Fig. 6 is a fragmentary elevational view 50 of the inner side of the door showing a differently shaped key hole,

Fig. 7 is an elevational view of the knob and spindle removed from the lock, with one section of one knob removed and

55 Fig. 8 shows side elevational and end

views of the key for releasing the lock at the outer side of the door.

Referring more in detail to the accompanying drawings, there is illustrated a portion of a door 1 and a door frame 2, the door 1 being provided with an edge socket 60 as shown in Figs. 2 and 4 for receiving a lock casing 3 while the adjacent edge of the door frame 2 is provided with a face plate 4 having a central opening therein registering with the bolt keeper socket 5, the face plate 4 being secured to the door frame by fastening devices 6 while the front wall 7 of the lock casing 3 carries upper and lower flanges 8 countersunk in the edge of the 65 door 1 and secured thereto by fastening devices 9.

The lock casing preferably comprises integral side and end walls, the corners of the casing adjacent the open side being provided with lugs 10 to receive fastening devices 11 for securing the face plate 12 of the lock to the casing. The forward end wall 7 of the lock casing is provided with a central opening 13 accommodating the projection 70 of the sliding latch bolt for reception in the keeper socket 5 as shown in Figs. 1 and 3.

As shown in Figs. 1 to 4, the integral side wall of the casing 3 carries a pair of arms 85 14 and 15 projecting in parallelism and having openings therein for the passage of the sliding latch bolt 16, the bolt 16 having a reduced shank portion 16' extending through the arm 14 while the head of the bolt projects through the arm 15. To hold the bolt forwardly projected, an expansion coil spring 17 surrounds the shank 16' of the bolt and engages at one of its ends the shoulder 14 and at its other end the cross 95 pin 18 extending through the bolt. The shifting mechanism for the sliding latch bolt 16 includes the formation of a socket 19 opening at the end of the bolt shank 16' as shown in Figs. 1 and 3 and into which 100 socket 19 a cylindrical lug projection 20 carried by a band 21 is received. A sleeve 22 is rotatable in the band 21 as shown in Figs. 1 and 3 and has an inwardly directed block projection 23 the inner edge of which 105 is provided with a cylindrical socket 24 communicating with a restricted passage 24' opening in the center of the cylinder 22. A knob spindle 25 shown in detail in Fig. 7 carries a longitudinal lug 28, the spindle 25 110

carries a longitudinal lug 28, the spindle 25 110

extending into the socket 24 in the cylinder block 23 with the lug 26 projecting into the restricted opening 24' of the cylinder block as shown in Figs. 1 and 3 to cause the cylinder to rotate with the spindle 25. The opposite ends of the spindle project through opposite sides of the door 1 as shown in Fig. 2 and a knob 27 attached to each end thereof, each knob being of two-part construction as shown in Fig. 7 and secured together by the pin 28, the sections of the knob inclosing the spindle extensions 29.

A device is provided for retaining the sliding latch bolt 16 in its locked position, 15 guide flanges 30 being provided upon the bottom wall of the lock casing and receiving a sliding frame 31 having a longitudinal slot 32 through which a transverse pin 33 extends to maintain the member 31 in position. One end of the sliding member 31 has an angular upstanding arm 34 projecting beyond the key receiving opening in the side of the casing and with which the key is adapted to be engaged for shifting the 25 sliding member 31. A pin 35 extends transversely of the casing adjacent the opposite end of the sliding member 31 and supports a journaled sleeve 36 carrying a depending arm 37 having at the lower end thereof a pin 38 extending into the slot 32 of the sliding member while a curved latch arm 39 is carried by the sleeve 36 and extends upwardly therefrom and passes through a guide bracket 40 secured to the side wall 35 of the casing 3 with the nose 41 of the latch arm extending through an opening in an angle extension 42 carried by the lower end of the bracket 15, a coil spring 43 surrounding the latch rod between the guide bracket 40 and the angle extension 42 of the bracket 15 normally to hold the nose 41 of the latch at the limit of its forward movement. The lower face of the sliding latch bolt 16 is projected with a recess 44 defining an abutment shoulder 45 against which the flat face of the latch nose is adapted to engage and limit the forward projecting movement of the sliding latch bolt as influenced by the spring 17.

50 A key of the type shown in Fig. 8 is employed for releasing the latch device from the outer side of the door 1, the key comprising a handle 46 having a shank including a straight blade section 47, a right angular offset 48 at the lower end thereof and an inclined blade portion 49 extending from the offset 48 having the lower end thereof substantially in alignment with the blade portion 47. An escutcheon plate 50 is secured to the outer face of the door 1 and carries a disk 51 rotatably mounted therein adjacent the lower end with an opening 52 therein corresponding to the key plate in cross section. An escutcheon plate 53 is 55 carried by the inner face of the door and

has a disk 54 rotatably mounted therein adjacent the lower end and is provided with a slot 55 having an end offset portion 56 for receiving a similarly shaped key, the slots 52 and 65 in the disks 51 and 54 respectively are aligned with each other through the lock casing 3 and extend inwardly of the angle arm 24 carried by the sliding member 31 for operating the latch device. 75

In the operation of the device, assuming that the sliding latch bolt 16 is in the position shown in Fig. 1 projected through the opening 13 in the casing wall 7 and into the keeper socket 5, the latch device comprising 80 the head 41 is engaged in the notch 44 in the lower face of the latch bolt and under influence of the spring 43 the bolt is maintained projected and prevented from being retracted by the turning of the knobs 27. 85 When it is desired to retract the sliding latch bolt 16, assuming that the door is to be opened from the outside as shown in Fig. 1, the key employing the relatively angular blade portions 47 and 49 is inserted in the 90 key slot 52 of the disk 51 with the inner end thereof positioned inwardly of the angle arm 34 of the sliding latch operating member 31. By rotating the key 46 to the position shown in Fig. 3, the blade 49 of the key engages the angle arm 34 to shift the sliding member 31 guided by the pin 33 and the guide 34 to rotate the sleeve 36 upon the shaft 35, moving the arm 37 to the sleeve and the curved latch arm 39, thereby lowering the latch head 41 from engagement with the sliding latch bolt 16 at which time the knob spindle 25 will be rotated to shift the ring 22 within the sleeve 21 effected by the lug 26 of the knob spindle locking the 95 spindle to the block 23 of the sleeve 22. Rotation of the spindle will cause a translating movement of the ring 21 and the connection 19 and 20 between the sleeve and latch bolt will withdraw the latch bolt against the tension of the spring 17 to the position shown 100 in Fig. 3 to free the projected end of the latch to remove the projected end of the latch from the keeper socket 5 in the door frame, at which time the door may be swung 105 to an open position. The key 46 may then be removed from the slot 52 and the upper end of the latch head 41 will engage the lower face of the sliding latch bolt 16. In locking the door, the sliding latch bolt 16 is 110 reversely shifted to the projected position shown in Fig. 1 by rotation of the knob spindle 25 to position the notch 44 in the lower end of the latch bolt for reception of the latch head 41, the spring 43 elevating the 115 latch head to automatically lock the door. To release the lock mechanism from the inner side of the door, a key conforming to the shape of the slot 55 shown in Fig. 6 is 120 employed with the inner end thereof posi- 125

tioned for engagement with the angle arm 34 of the sliding member 31 and the operation by rotating the key is the same as above described.

5 While there is herein shown and described the preferred embodiment of the invention, it is nevertheless to be understood that minor changes may be made therein without departing from the spirit and scope of the invention as claimed.

10 What is claimed as new is:

1. A door lock of the type described comprising a casing, a sliding latch bolt mounted therein, a latch device pivotally mounted 15 within the casing and comprising a downwardly extending arm and an upwardly curved arm, a latch head carried by the upper end of the curved arm, a coil spring surrounding the curved arm and engaging the 20 head of the latch device for normally forcing the same into positive engagement with the sliding latch bolt to hold the same in locked position, a sliding member guided in its movements by the lower wall of the casing 25 and connected to the downwardly extended arm of the latch device, an angle arm extending upwardly from one end of the sliding member and adapted to be engaged by a key projection within the casing for 30 shifting the sliding member to free the latch device from engagement with the sliding latch bolt and a knob spindle removed with the sliding latch bolt to retract the same to inoperative position.

35 2. A door lock of the type described comprising a casing, a sliding latch bolt mounted therein, a coil spring surrounding the latch bolt co-operating with the casing and bolt to hold the bolt normally projected from 40 the casing, a sleeve member having a swivel connection with the inner end of the sliding latch bolt, a tubular sleeve within said ring

member and a knob spindle extending into said sleeve and eccentrically connected thereto for shifting the ring member and sliding 45 latch bolt swivelly connected thereto to retract the same to inoperative position within the casing.

3. A door lock of the type described comprising a casing, a sliding latch bolt mounted 50 therein, a coil spring surrounding the latch bolt co-operating with the casing and bolt to hold the bolt normally projected from the casing, a sleeve member having a swivel connection with the inner end of the 55 sliding latch bolt, a tubular sleeve within said ring member, a knob spindle extending into said sleeve and eccentrically connected thereto for shifting the ring member and sliding latch bolt swivelly connected thereto 60 to retract the same in inoperative position within the casing, and a latch device associated with the sliding latch bolt for holding the same in locked projected position.

4. A door lock of the type described comprising a casing, a sliding latch bolt mounted 65 therein, a coil spring surrounding the latch bolt co-operating with the casing and bolt to hold the bolt normally projected from the casing, a sleeve member having a 70 swivel connection with the inner end of the sliding latch bolt, a tubular sleeve within said ring member, a knob spindle extending into said sleeve and eccentrically connected thereto for shifting the ring member and 75 sliding latch bolt swivelly connected thereto to retract the same to inoperative position within the casing and a key operated latch device associated with the sliding latch bolt to hold the same in projected locked position.

40 In testimony whereof I affix my signature.

SIMO GJUKIC.
